(57) **CLAIM**

The ornamental design for a writing instrument, as shown and described.

DESCRIPTION

FIG. 1 is a front elevational view of a writing instrument showing my new design;

FIG. 2 is a right side elevational view thereof;
FIG. 3 is a left side elevational view thereof;
FIG. 4 is a rear elevational view thereof;
FIG. 5 is a top plan view thereof;
FIG. 6 is a bottom plan view thereof;
FIG. 7 is a perspective view obliquely from the front and below thereof;
FIG. 8 is a perspective view obliquely from the rear and above thereof;
FIG. 9 is a front elevational view of a second embodiment of my design of FIG. 1;
FIG. 10 is a right side elevational view thereof;
FIG. 11 is a left side elevational view thereof;
FIG. 12 is a rear elevational view thereof;
FIG. 13 is a top plan view thereof;
FIG. 14 is a bottom plan view thereof;
FIG. 15 is a perspective view obliquely from the front and below thereof;
FIG. 16 is a perspective view obliquely from the rear and above thereof;
FIG. 17 is a front elevational view of the body of the writing instrument of FIG. 1 shown with the cap member removed for clarity of illustration;
FIG. 18 is a right side elevational view thereof;
FIG. 19 is a left side elevational view thereof;
FIG. 20 is a rear elevational view thereof;
FIG. 21 is a top plan view thereof;
FIG. 22 is a bottom plan view thereof;
FIG. 23 is a perspective view obliquely from the front and below thereof;
FIG. 24 is a perspective view obliquely from the rear and above thereof;
FIG. 25 is a front elevational view of the cap member of the writing instrument of FIG. 1 shown separately for clarity of illustration;
FIG. 26 is a right side elevational view thereof;
FIG. 27 is a left side elevational view thereof;
FIG. 28 is a rear elevational view thereof;
FIG. 29 is a top plan view thereof;
FIG. 30 is a bottom plan view thereof;
FIG. 31 is a perspective view obliquely from the front and above thereof;
FIG. 32 is a perspective view obliquely from the rear and below thereof;
FIG. 33 is a front elevational view of the writing instrument of FIG. 1 shown in an exploded condition;
FIG. 34 is a right side elevational view thereof;
FIG. 35 is a left side elevational view thereof;
FIG. 36 is a rear elevational view thereof;
FIG. 37 is a top plan view thereof;
FIG. 38 is a bottom plan view thereof;
FIG. 39 is a perspective view obliquely from the front and below thereof; and,
FIG. 40 is a perspective view obliquely from the rear and above thereof.

UNITED STATES PATENT AND TRADEMARK OFFICE
CERTIFICATE OF CORRECTION

PATENT NO. : Des 437,888 S
DATED : February 20, 2001
INVENTOR(S) : Siegfried Keil

Page 1 of 1

It is certified that error appears in the above-identified patent and that said Letters Patent is hereby corrected as shown below:

Title page.

Item [12], delete "**Brigg et al.**" and insert therefor -- **Keil** --.

Item [75], Inventors, delete "**Hariolff BriggI**, Boebingen (DE)".

Signed and Sealed this

Sixteenth Day of July, 2002

Attest:

Attesting Officer

JAMES E. ROGAN
Director of the United States Patent and Trademark Office
